UNITED STATES PATENT OFFICE.

OTIS D. CROCKER, OF CLEVELAND, OHIO.

DESIGN FOR A VAPOR-STOVE.

SPECIFICATION forming part of Design No. 12,231, dated April 26, 1881.

Application filed March 18, 1881. Term of patent 3½ years.

To all whom it may concern:

Be it known that I, OTIS D. CROCKER, of Cleveland, in the county of Cuyahoga and State of Ohio, a citizen of the United States, and a resident of above-named place, have invented and produced a new and original Design for Vapor-Stoves, of which the following is a specification, reference being had to the accompanying print, forming part thereof.

10 In the print is shown a view in perspective of a vapor-stove constructed according to my design.

A is the top or table of a vapor-stove, provided with three circular openings, *a a a*, having gratings, beneath which are located the vapor-burners. The openings *a a a*, it will be observed, instead of being in a straight line, are arranged in a curved line, thus giving a curved shape and appearance to the front and rear lines of said table. The corners are rounded, having a notched ogee form. The said table is also ornamented with appropriate scroll-work.

B is a removable open scroll-work shelf, fitted to fill the curved space at the rear side of the table, and thus making the rear side straight.

C C are removable rounded open-work end shelves for extending the top, as shown.

D D are the legs, which are made in straight 30 lines, the cross-bars being angular in form, presenting to the eye a pleasing appearance. The lower cross-bar is ornamented with a diamond-shaped open lattice-work, *d*, on its upper edge.

Having described my invention, I claim—

1. In a design for vapor-stoves, the table or top A, having its open gratings *a a a* arranged in a curved line, its front line in a convex and its rear line in a concave form, and having 40 the corners rounded, as shown and described.

2. In a design for vapor-stoves, the table or top A, having its open gratings *a a a* arranged in a curved line, its front line convex, and its rear line in a concave form, and having the 45 corners rounded, as shown, provided with the rear shelf, B, and the end shelves, C C, substantially as set forth.

3. In a design for vapor-stoves, the legs D D, having the perpendicular lines broken and 50 offset and the cross-bars angular, as shown and described.

OTIS D. CROCKER.
